US00D496653S1

(12) **United States Design Patent** (10) Patent No.: **US D496,653 S**
 Townsend et al. (45) Date of Patent: **** Sep. 28, 2004**

(54) **COMMUNICATION DEVICE**

(75) Inventors: **David P. Townsend**, Lakewood, IL (US); **Daniel T. Berg**, Antioch, IL (US); **Claudio Santiago Ribeiro**, Evanston, IL (US)

(73) Assignee: **Motorola, Inc.**, Schaumburg, IL (US)

(**) Term: **14 Years**

(21) Appl. No.: **29/188,395**

(22) Filed: **Aug. 18, 2003**

(51) LOC (7) Cl. **14-03**

(52) U.S. Cl. **D14/240**; D14/358; D14/433

(58) Field of Search D14/137, 138, D14/218, 147-148, 247-249, 144, 58, 341-347, 426, 242, 433, 432, 453, 240, 356, 155; 379/433.01-433.13, 434, 419, 420.01-420.04, 428.01-428.02, 440, 368-370; 455/550.1-90.3; D10/104, 106; D13/168; 340/425.5, 539.1, 539.11; 345/168, 169; D21/329, 331, 517; D16/202, 208; 361/685, 686
